UNITED STATES PATENT OFFICE

HARRY D. AYARS, OF SALEM, NEW JERSEY

DEPOSITOR

Application filed April 20, 1927. Serial No. 185,247.

The present invention belongs to the art of depositors, generally speaking, and is particularly adapted as a salter for can filling machines, that is, more especially for depositing discs of salt into cans of tomatoes consecutively as the cans pass along a discharging outlet. It is obvious that while this apparatus is designed for use as a salter in connection with a can filling machine, it may also be used for depositing pulverized or granulated or similar substances into containers.

It is the purpose of this invention to vary the size of the deposit, according to the use for which the machine is adapted.

15 The present construction of depositor is of the drop feed type, it being another purpose to measure the deposit, in combination with automatic means for discharging the deposit, which is in the form of a disc.

20 Heretofore some of the machines of this type for depositing requisite quantities of material in containers, include screw feeds, and it has been found that the material being deposited or discharged, especially if it be

25 salt, binds in the screw, and the necessary amount fails to properly discharge, hence another purpose is to provide, in a depositor of the present character, means for not only agitating the granulated or pulverized sub-

30 stance, more especially salt, in conjunction with means which insure the forming of the substance to be deposited into discs, that is to cause the substance to feed into disc forming openings as a member having such open-

35 ings is about to pass a discharging or outlet opening.

40 A further purpose is to provide, in a depositor of this kind, an automatic discharging plunger to accurately engage through an outlet opening, and thereby force the substance, such as salt, in the form of a disc from the opening and cause it to deposit into a can filled with tomatoes.

45 It is obvious that by increasing the thickness of the rotating plate or member which has a series of disc forming openings therein, it is possible to increase the thickness of the disc of substance. A certain quantity of salt is required for each can of tomatoes, and the present showing is designed for depositing

discs of salt of the requisite size to make up the necessary supply of salt for the tomatoes. Other seasoning, such as possibly sugar, for certain food products in cans, may have to be increased in quantity, according to the food products being canned.

55 A still further purpose is to provide means for operating a rotating plate or member with the disc forming openings therein, at all times in the same direction, but intermittently, hence the machine being of the drop feed type.

60 A still further purpose is to provide a plurality of telescopically arranged rotating members, one within the other, one carrying the agitator, the other rotating the intermittently movable plate with the disc forming openings therein, and the other for actuating a cam, which in turn imparts movement to the plunger for causing the discharge of a disc of seasoning such as salt, said plurality of telescopically arranged members acting 65 to derive power from the same source.

70 It is to be understood that the particulars herein given are in no way limitative, and that while still keeping within the scope of the invention, any desired modification of details and proportions may be made in the construction of the appliance according to circumstances.

75 The invention comprises further features and combination of parts to be hereinafter set forth, shown in the drawings and claimed.

In the drawings:—

80 Figure 1 is a plan view of the improved depositor or salter especially adapted for a tomato can filler.

85 Figure 2 is a view in side elevation of the depositor or salter constructed in accordance with the invention.

90 Figure 3 is a sectional view on line 3—3 of Figure 1.

95 Figure 4 is a view mostly in elevation and parts in section, more especially showing the construction of the salter or depositor.

100 Figure 5 is a perspective view of the rotating plate which has the disc forming openings therein, said plate being of increased thickness to that shown in Figure 3.

105 Figure 6 is a plan view and partly in sec-

tion on line 6—6 of Figure 4 showing the means for driving the plurality of telescopic rotating members.

Figure 7 is a detail view showing the 5 plunger for discharging a disc of salt, just in the act of entering one of the disc forming openings in the rotating plate.

Figure 8 is a detail view of the cam member for causing the downward movement of 10 the plunger which discharges a disc of salt or other material.

Referring to the drawings—1 identifies an operating shaft of a filling machine, which in the present instance is a tomato filler. This 15 shaft carries a rotating plate 2, which supports cans 3 or other containers for conveying them along the discharging opening of the depositor. The shaft 1 carries a sprocket 4 and a rotating arm 5. The shaft is driven 20 through the medium of a gear 6 of the required diameter, and which may derive its power from the filling machine, not entirely shown. The gear 6 meshes with the gear 7 on the shaft 1.

25 The salter or depositor comprises a base 8, which is supported by the bars 9, which in turn may be supported in any suitable manner, possibly at 10, on the frame 11 of a filling machine.

30 The depositor also comprises three telescopic members or shafts 12, 13 and 14, the first one being solid throughout with its upper end at 15 carrying an agitator 16, while its lower end carries a sprocket 17 about which 35 a chain 18 engages, the latter receiving power from the sprocket 4 on the shaft 1. The agitator consists of a spider 19 with a plurality of depending arms or rods 20, which extend into and terminate at the bottom of a hopper 40 21 of the depositor or salter. The lower extremities of the arms or rods 20 carry resilient 45 agitator blades 22, for scraping the interior of the hopper and thereby agitating the salt or other substance to be deposited.

45 The hopper 21 is mounted upon the plate 8, and may be any shape and of approved type.

The shaft 13 is hollow and the solid shaft 50 12 passes through it, while the shaft 14 is hollow and telescopes the shaft 13 exteriorly. The lower end of the shaft 13 carries a disc 23 having a plurality of teeth 24, there being four in number at diametrically opposite points, so that an intermittent movement 55 may be imparted to the disc and a corresponding movement to the shaft 13, for the purpose of actuating a plate 25 on the interior of the hopper at the bottom thereof. The agitator spring plates 22 ride over this 60 plate 25, and thereby not only act to scrape the salt or other pulverized substance from the face of the plate, but also from the side of the hopper, especially near the bottom thereof. Rising from the plate 25 is a cone 65 26 rotating with the plate and this cone also

acts to agitate the salt or other substance to be deposited. However, the member 26, while being conical, is not quite as high as the outer wall of the hopper. The purpose of the cone is to keep the salt toward the outer portion 70 of the bottom of the hopper, that is adjacent the outer wall. The plate 25 is provided with a plurality of disc forming openings 27, into which the salt or other pulverized material enters, it being scraped thereinto by the 75 spring agitating blades 22.

Referring to Figure 1 of the drawings it will be noted that the hopper 21 has a flat perpendicular wall, especially at the location near where the salt or other pulverized substance is discharged or deposited. The flat wall is positioned a substantial distance in toward the central cone 26, sufficiently to permit the disc forming openings 27 to pass exteriorly of the hopper, that is beyond the flat 80 perpendicular wall 28 of the hopper, thereby permitting the plunger head 29 of the plunger rod 30 to pass through each of the openings 27 as they pass beyond the wall and register with an opening 31 in the plate 8. 85 The plunger rod is guided in a bearing 32 of an arm 33, which is bolted or otherwise secured at 34 to the plate 8. Fixed on the plunger rod 30 is a collar 35 by means of a set-screw 36, and above and below the collar in surrounding relation to the plunger rod 30 are coiled springs 37 and 38, the former being of greater tension than the latter, so as to provide quick action for the plunger 90 rod when the plunger head 29 is in the act 100 of passing through the registering openings 27 and 31.

Also rising from and secured to the plate 8 as at 39 is an upright 40 having an opening 41 through which a bar 42 is guided. The 105 upper lateral end of the bar 42 slidably carries the plunger rod 30, said rod being held in position in the extremity of the lateral arm by means of a set bolt 43, the spring 37 acting between the collar 35 and the extremity 110 of the lateral arm of the bar 42.

The lower end of the bar 42 passes through the plate 40 and carries an anti-frictional roller 44, with which a cam 45 engages for actuating the bar 42 in a downward direction, and since it carries the plunger rod 30, the plunger head 29 is depressed by a spring 37 under action of the bar 42 against 25, as in Figure 7, so that it will snap into the opening 27 when in registry with the opening 31.

It is obvious that by adjusting the collar 35 upwardly on the plunger rod 30, the greater distance the plunger head 29 will pass through the registering openings 27 and 31. By adjusting the collar 35 downwardly on the plunger rod 30 the less distance the plunger head 29 will pass through the registering openings 27 and 31.

The cam 45 is mounted upon an intermit- 120

tent oscillating arm 46, which is carried by the upper end of the exterior shaft or sleeve 14, the lower end of which in turn carries a disc 47 secured in position by a set screw or bolt 48.

Pivoted to the disc 47 by means of a pin 49 is a link or bar 50, which in turn is pivoted on a pin 51 of the arm 5 on the lower end of the shaft 1. Obviously the shaft 1 of the filling machine, not shown, receives a continuous rotary motion, and due to the arm 5 being carried thereby, it rotates in a corresponding direction, hence imparting a reciprocatory motion to the bar or link 50. The bar or link 50 being pivoted to the plate or disc 47, imparts an intermittent movement backwards and forwards to the disc or plate 47, and hence imparts a corresponding movement to the sleeve or shaft 14. Obviously about when the opening 27 is registering with the opening 31, the cam 45 is just in the act of engaging with the roller 44, hence starting the bar 42 on a downward movement against the action of the spring 38 (which is interposed between the collar 35 and the bearing 32), the spring 37 acting to overcome the tension of the spring 38 and depressing the plunger head 29 due to the action of the bar 42 against 25 as in Figure 7, so that it will snap with quick action into the opening 27 when in registry with opening 31. The entering of the plunger head in the registering openings 27 and 31 is accomplished when the cam 45 has moved the arm 42 sufficiently, and the plate or disc 23 has been rotated sufficiently to carry the plate 25 far enough to cause a registering of the openings 27 and 31. A pawl 52 is pivotally mounted at 53 on an arm 54 which is carried by the plate or disc 47 and this pawl 52 is spring tensioned through the medium of a leaf spring 55. The pawl 52 is designed to engage with any one of the several notches or teeth 56 of the disc or plate 23, hence imparting a rotating movement to the disc or plate 23 intermittently. At the end of each intermittent motion of the plate or disc 23, one of the openings 27 registers with the opening 31, and as this registering action takes place the plunger head 29 enters the two openings 27 and 31, and thereby deposits a disc of salt or other seasoning into a passing can.

Obviously by increasing the thickness of the plate 25 it is possible to increase the size or thickness of the disc of substance to be discharged from the openings 27 and 31. Should the material being deposited be other than a seasoning substance, for instance a talcum or similar cosmetics or any other material to be filled in a small container, it is necessary to increase the size of the plate 25 and possibly make the opening larger in diameter, though not necessarily.

Regular tests and experiments have shown that this salter will operate accurately,

whether the salt or other seasoning be dry, damp or even wet. Experiments have shown that better results are attained where the salt is damp.

Also carried by the arm 46 is an angular guarding cam 57, which positions below the roller 44 as the plunger head descends in order to enter the registering openings 27 and 31. In Figure 5 the plate 25 is shown as substantially thicker than that in Figure 3, showing it possible to so increase the size of the plate as to provide for forming discs of salt or other substance of increased thickness.

In the operation the cans containing tomatoes are passed under the registering openings 27 and 31 through the medium of the table or rotating disc 2, and as they pass under the openings the seasoning such as salt or the like is measured in disc form and conveyed exteriorly of the hopper, that is beyond the flat perpendicular portion 28 of the hopper, then the plunger descends and forces the disc of salt from the openings 27 and 31 into each individual can. In this operation the plate 25, the plunger head 29 and its rod and the cams 45 and 57 receive power or are operated by the shaft 1, due to the individual operative connections between the shaft 1, the sprocket 17, the disc 23 and the disc or plate 25. It is to be noted that the sprocket chain 18 which passes over the sprocket 17, also engages with an idler sprocket 58, thereby preventing the sprocket from engaging with the link or bar 50 during its actions.

The invention having been set forth, what is claimed is:

1. In a depositor, the combination with a hopper to contain a substance to be deposited, of receiving, measuring and conveying means consisting of a revoluble element with openings therein for a disc deposit of said substance, means for imparting an intermittent movement to said element, a fixed base for said hopper having an opening beyond the wall of the hopper with which any one of the first openings may register, means consisting of a spring tensioned plunger adapted to force the deposit from the registering openings, said intermittent actuating means provided with a device to swing back and forth concentric with said intermittent means, and means carried by the plunger to cooperate with the device at intervals to actuate the plunger at a predetermined moment when said openings register.

2. In a depositor having a hopper provided with measuring and conveying means for a deposit of substance contained in the hopper, a spring tensioned plunger adapted to force the deposit from the measuring and conveying means and provided with a guide element movable with the plunger, and means intermittently actuated on an arc concentric with

the hopper to depress the guide element, and thereby in turn intermittently actuating the plunger.

3. In a depositor having a hopper provided with measuring and conveying means for a deposit of substance contained in the hopper, a spring tensioned plunger adapted to force the deposit from the measuring and conveying means and provided with a guide element movable with the plunger, and means intermittently actuated on an arc concentric with the hopper to operate the guide element, and thereby intermittently actuating the plunger, said means which operates on an arc concentric with the hopper comprising an actuating cam and a guard cam, to insure positive movement of the guide element.

4. In a depositor having a hopper provided with measuring and conveying means for a deposit of substance contained in the hopper, a spring tensioned plunger adapted to force the deposit from the measuring and conveying means and provided with a guide element movable with the plunger, and means intermittently actuated on an arc concentric with the hopper to operate the guide element, and thereby intermittently actuating the plunger, and means for regulating the distance of movement of the plunger, whereby its position through the measuring and conveying means may be governed.

5. In a depositor, a hopper for containing a substance to be deposited and having means for measuring and conveying a deposit of said substance to a position to be discharged, means for actuating the measuring and conveying means intermittently in one direction, agitating means rotatable in the hopper continuously in an opposite direction to the intermittent movement of the measuring and conveying means, a plunger element for discharging the measured deposit from the measuring means, opposed tensioning means for the plunger element, a device for regulating the opposed tensioning means for governing the distance of the plunger element through the measuring means, a guided device connected to the plunger element, and means operable intermittently back and forward on an arc concentric with the center of the hopper for imparting movement to the guided device for actuating the plunger element at the time the measuring means reaches the discharging position.

6. In a depositor, a hopper to contain a substance to be deposited, having means to measure the substance in given deposits intermittently, the deposits being carried to a discharge position, a reciprocating discharge element to discharge the deposits from their discharge positions and having a guide arm mounted in bearings adjacent the side of the hopper, opposed tensioning means for the reciprocating discharge element, means on the discharge element for regulating the opposed

tensioning means, thereby regulating the movement of the discharge element through the measuring means, and means intermittently actuated back and forth on an arc concentric with the hopper and cooperating with the guide arm for imparting movement to the discharge element.

7. A depositor for a condiment substance having a hopper provided with a measuring means operable to a discharging position intermittently, a discharging element for a deposit of said substance from the measuring means, means for actuating the plunger element, opposed tensioning means for the plunger element, and a device carried by and adjustable on the plunger element for regulating the opposed tensioning means to govern the movement of the plunger element through the measuring means.

In testimony whereof he affixes his signature hereto.
